ROTARY INTERNAL COMBUSTION ENGINE

Henry Schulman, Pangbourne, England

Application June 22, 1932, Serial No. 618,788
In Great Britain June 30, 1931

2 Claims. (Cl. 123—43)

This invention relates to rotary internal combustion engines of the type comprising a multi-cylinder unit consisting of a concentric group of toroidal cylinders, rotatable about their common centre, and a multi-piston unit comprising a corresponding group of pistons, the pistons working within the cylinders and the two units being so rotatable about said common centre and in the same direction as to produce relative reciprocation as between each piston and its cylinder. In engines of this type, the various strokes of the internal combustion cycle are performed simultaneously in different cylinders of the group and the relative reciprocation referred to is obtained by momentarily holding one of the units during the power stroke of the engine, automatic detent mechanism being provided for this purpose.

The object of the present invention is to provide an improved construction of engine of the type referred to, as will hereinafter appear.

According to the present invention, a rotary internal combustion engine of the type referred to comprises in combination an annular rotary multi-cylinder unit, a co-operating rotary multi-piston unit coaxial with the cylinder unit, valve and ignition means operable to occasion explosions alternately on opposite sides of the pistons, those on one side producing power strokes of the cylinder unit about the common axis of rotation of the units and those on the other side producing auxiliary strokes of the piston unit about said common axis and in the same direction as the strokes of the cylinder unit, the strokes of the piston unit being non-power strokes serving simply to return the two units to their initial relative positions at the commencement of the power stroke of the cylinder unit and means to prevent reverse rotation of each unit during the strokes of the other unit, the cylinder unit having a moment of inertia substantially exceeding that of the piston unit and constituting thereby a flywheel in the engine from which the power of the engine is arranged to be transmitted.

Moreover, by arranging that the cylinder unit shall function as a flywheel in the engine and that the power from the engine shall be transmitted from this flywheel, in contrast to the known arrangement wherein both rotating units perform power strokes and transmit their rotary thrust in turn through the intermediary of free-wheel clutch mechanism to a flywheel common to them both and from which the power of the engine is transmitted, the important advan-

tage is realized of further weight economies and in addition further lessening of complication of parts in the engine; in other words, a lighter, simpler and less expensive engine design is provided and one, moreover, which will be less liable to failure in operation than the prior design referred to.

It will be understood, of course, that in an engine in accordance with this invention, the strokes of the piston unit in addition to returning the two units to their initial power stroke firing positions in relation to one another serve at the same time to scavenge the exhaust gases from the previous power stroke and compress the mixture in other cylinders for the next succeeding power stroke.

According to a further feature of the invention, the construction and arrangement of parts may be one in which the cylinder unit comprises a hollow annulus circumferentially slotted completely around the inner periphery of its wall and sub-divided interiorly into a plurality of double-ended cylinders by a series of equally spaced transverse partitions, and the piston unit comprises a group of equally spaced pistons working one within each of said cylinders and mounted upon a carrier member which is external to the cylinder annulus and comprises a part which in a gas tight manner blocks the circumferential slot therein. With such a construction, as will be appreciated, it is readily possible to employ quite a large number of pistons in the engine and correspondingly, of course, a large number of double-ended cylinders, for a gap has not to be interposed in the cylinder wall between opposite ends of the cylinders to accommodate the oscillations of a radial piston rod or its equivalent connecting the double-acting piston within the cylinder to the part of the piston unit exterior to the cylinder.

Conveniently and with advantage, the cylinder annulus may be constructed in two opposed complementary halves, with the joint between them lying in the medial plane of the annulus, the two annulus halves being bolted together around the outer circumference of the annulus.

One convenient construction of an aircraft propulsion plant in accordance with the invention will now be described by way of example, with reference to the accompanying drawings, of which:—

Figure 1 is an axial view of the unit, with certain of the cylinders broken away to show the pistons;

Figure 2 is a corresponding central longitudinal section through the unit;

Figure 3 is a section through one of the pistons and the ends of two adjacent cylinders; taken 5 along the line 3—3 of Figures 1 and 2;

Figures 4 and 5 are respectively a fragmentary longitudinal section and a fragmentary transverse section through the cylinder-unit showing an alternative method of construction of the piston-unit;

Figure 6 is a fragmentary central longitudinal section through the unit showing a modification hereinafter described, and

Figure 7 is a corresponding axial view.

Like reference numerals indicate like parts in the various figures.

The engine comprises an annular cylinder-unit embodying a group of twelve cylinders, three in each quarter of the unit. The said cylinder-unit 20 is built up of two complementary halves 1, 2 each in the form of a dished annulus. The two halves 1, 2 are bolted together by means of closely spaced bolts 3 passing through flanges or lugs 4 cast to receive them around the outer peripheries of the 25 halves 1, 2. As shown in Figure 2, the annular cavity between the two complementary cylinder halves 1, 2 is of circular radial cross-section, and located at regularly spaced intervals around this cavity are a succession of twelve radial partitions 30 5, bolted in place by means of bolts 5' reaching completely through the cylinder unit. These partitions have a gas-tight fit with the walls of the cylinder halves and they constitute conjointly with said halves, a group of concentric arcuate cylinders. The unit is revolvably mounted upon a 35 fixed shaft 7.

Revolvable also upon said shaft 7 in the same direction as the cylinder unit is a disc 8. The outer peripheral margin of this disc is, as clearly 40 shown in Figure 2, inserted between the inner peripheral margins of the two complementary cylinder halves 1, 2, flanges 9 being formed on these margins to extend the surface-area of contact thereof with the margin of the disc 8, it being 45 understood, of course, that there must be no escape of gas past these surfaces, either to or from the interior of the cylinders. To this end, packing means, for example, a series of concentric packing rings 10, are preferably provided between 50 the said surfaces.

Mounted upon the periphery of the disc 8 are a series of twelve pistons 11, equally spaced around the circumference of the disc and accommodated each within a cylinder of the cylinder unit.

The cylinder unit is provided with two sets of hollow radial spokes 12, 13 projecting from bosses 14, 15 revolvable on the shaft 7. The outer ends of these spokes 12, 13 are connected to lateral branches projecting from and integral with the 60 cylinder-unit.

The fixed shaft 7 is hollow and accommodates a supply conduit 16 for carburetted fuel for ignition in the cylinders. This conduit 16 feeds the fuel to an annular induction manifold 17 extending around the inner wall of the shaft 7 in the general plane of the boss 15. This manifold has in its outer wall outlet ports 18 which register with an annular port-passage 19 in the boss 15. This port-passage 19 in turn communicates with the 70 interior, at the inner end, of the hollow spokes 13. At the outer end, the interior of these spokes communicates with fuel passages 20 in the rearward (right hand in Figure 2) lateral branches aforesaid projecting from the cylinder-unit.

In said rearward lateral branches are mounted

inlet valves 21 which control the admission of carburetted gas mixture from the passages 20 in the branches to the spaces between the partitions 5 and the pistons 11 on either side thereof.

Figures 2 and 3 clearly illustrate the construction in this respect. As shown in these figures, each lateral inlet branch has in it two passages 20 controlled, respectively, by two inlet valves 21. The gas mixture after passing the valve 21 is admitted, in each case, directly into the cylinder by 10 way of a circumferential inlet port 22.

The lateral branches projecting from the other side of the cylinder unit constitute exhaust branches. They are formed with internal outlet passages 23 leading from circumferential outlet ports 24 in the walls of the cylinders. These outlet passages 23 are separately controlled by exhaust valves 25, and the exhaust gases, after passing the valves 25 enter exhaust manifolds 26. From the ends of these manifolds the gases 20 pass, by way of ports 27, into the interior of hollow propeller blades 28, mounted upon the periphery of the cylinder-unit and provided in their faces, near the extremity of the blade, with exhaust outlet holes 29 communicating with the 25 atmosphere.

The inlet and exhaust valves 21, 25 are actuated, of course, in time with one another and with the relative reciprocation of the pistons 11 and the cylinders within which they work. Their 30 actuating mechanism (not shown) may take any convenient form. For example, it may comprise a system of cam-discs engaging shoes or rollers on the inner end of the valve stems, such for example as shown generally in the patents to 35 Arthur 1,219,795 dated March 20, 1917; Oldham 1,212,100 dated January 9, 1917, etc.

In order to obtain the relative reciprocation of the pistons in their cylinders, the two units are provided with detent means operable to prevent 40 their backward rotation when the unit which is performing its firing stroke is moving forwardly.

The said detent means may take any convenient form. In the form shown, it comprises a disc 30 positioned adjacent one side of the disc 8 45 and mounted upon and stationary with the shaft 7, and co-operating with the periphery of this disc, a series of wedging dogs 32 pivotally mounted upon and carried by the disc 8 and normally held in light rubbing engagement with the periphery of the disc 30 by compression springs 33. A second disc 31 is positioned adjacent the opposite side of the disc 8 and is likewise mounted upon and stationary with the shaft 7. Co-operating with the disc 31 is a second series of wedging 55 dogs 32', pivotally mounted on the inner surfaces of the radial spokes 12 of the cylinder unit and rotating therewith, these dogs 32' having co-operating compression springs 33' and corresponding in construction and operation to the 60 construction and operation of the dogs 32 and springs 33 above referred to.

As will be understood, these two sets of dogs 32 and 32' operate momentarily to prevent backward rotation of the parts upon which they are 65 mounted, by permitting relative rotation of the pivots of the dogs and the discs 30 and 31 in one direction only, namely, the direction of rotation of the piston and cylinder units. The dogs immediately resist any tendency to rotation in the 70 opposite direction by wedge-gripping the peripheries of the discs 30, 31. These peripheries are preferably grooved in a circumferential direction, as shown, to extend their surface-area of engagement with the dogs.

In an alternative construction of the detent means (shown in Figures 6 and 7), the wedging dogs 32 may each be mounted upon a pair of pivots 32a, 32b, located one (32a) beyond the other (32b) in a direction radial to the axis of the shaft 1, and the radially inner one slightly in front of the outer, as shown in Figure 7, in a circumferential direction opposed to the direction of rotation of the piston disc 8. The outer pivot 32a of these two is mounted, as before, upon the face of the piston disc 8 and the inner pivot is mounted upon the periphery of a pair of discs 32c disposed one on either side of the detent discs 30 and 31 and freely revoluble around the shaft 1 in unison with the piston disc, being rotated around said shaft with this disc by reason of their interconnection with it through the medium of the double-pivoted wedging dogs. With this arrangement, the wedging action of the dogs is highly positive, as will be appreciated, for, upon the commencement of the operative thrust through the dogs from the piston unit or the cylinder unit, as the case may be, the dogs immediately pivot slightly about their inner pivots and at once bite on to the grooved peripheries of the discs 30 and 31 with which they function.

The engine also comprises a magneto 34 and a lubricating pump 35, these mechanisms being driven by a gear wheel 36 rotatable with the boss 30 and meshing with pinions 37, 38, fast, respectively, with the spindles of the magneto 34 and pump 35.

The ignition means of the engine comprises, as usual, sparking plugs. These plugs 39 are fitted in the cylinder walls close to the partitions 5 which separate the cylinders. The electric leads from the plugs are led down to the interior of the fixed shaft 1 by way of the hollow spokes 12 and leading-in tubes 40 from whence they are led along said shaft 1 to the distributor of the magneto. The means for securing the ignition of the compressed charges at the right moment is not indicated, but any convenient ignition means may be employed so as to ignite the charges in the cylinders when the cylinder-units and piston-units come into their proper working positions. The ignition system may be either a system of coil ignition or a system of magneto ignition. In the latter event, the magneto 34 would, as usual, incorporate a distributor connected up in an appropriate manner, well understood in the art, to the several sparking plugs 39. If, on the other hand, a system of coil ignition be employed, the magneto 34 would be substituted by a suitable generator which, as usual would supply current to a battery, in turn wired up to the plugs 39 through the intermediary of an induction coil, make-and-break device, and distributor, the generator preferably, moreover, being provided with a direct connection to the induction coil by-passing the battery. As suggestive of a form of ignition system which may be employed, attention is invited to Figure 6 of the patent to Edqvist, No. 1,108,980 dated September 1, 1914.

The engine operates on the principle of the four-stroke cycle. This will be clear from the following description of the operation of the engine, carrying one of the cylinders, A, completely through the four strokes of the cycle.

It will be assumed that the cylinder unit is just about to commence to stroke, against the reaction of the piston unit, which during the stroke of the cylinder unit will be prevented from backward rotation by the detent action of the wedging dogs 32 and the disc 30. At this junc-

ture, there is a charge of combustible mixture in the forward part *a* of the cylinder A compressed in readiness for firing, this charge having been drawn into the said part of the cylinder during the previous stroke of the cylinder unit and having been compressed therein during the stroke of the piston unit following that previous stroke of the cylinder unit. Firing now takes place of the said compressed charge in the forward part *a* of cylinder A, with the result that the cylinder 10 unit moves forward against the reaction of the piston unit as described above. During this stroke of the cylinder unit, a charge of combustible mixture, previously drawn into the rear part *a* of the cylinder A during the stroke of the piston unit 15 immediately preceding the current stroke of the cylinder unit, becomes compressed in readiness for firing to move the piston unit forward through its stroke, which now occurs, the cylinder unit being prevented this time from backward rotation 20 by the wedging dogs 32 co-operating with disc 31. At the same time, that is to say, during the stroke of the cylinder unit and the expansion of the gases of combustion in said part *a* of cylinder A, the products of combustion of the said 25 preceding stroke of the piston unit in the rear part *b* of the next cylinder B of the unit become scavenged out of this part *b* while in part *b* of said cylinder B a fresh charge of combustible gases is drawn in, in readiness to be compressed 30 during the next stroke of the piston unit. During the stroke of the cylinder unit, there takes place, therefore, on the rear side of the partition or cylinder end 5 a firing and expansion of the 35 power-stroke gases of combustion and on the forward side a scavenging of the products of combustion of the non-power stroke gases of combustion of the last preceding stroke of the piston unit. At the same time, there takes place on the rear side of the cylinder end 5 of the adjacent 40 cylinder B a suction in of a fresh power-stroke charge of combustible gases, to be compressed during the next stroke of the piston unit, and on the forward side a compression of the non-power stroke charge previously drawn in during said 45 preceding stroke of the piston unit. This cycle, involving during alternate strokes of the cylinder unit, compression at the rear end of the cylinder and firing at the forward end and during the intervening strokes, scavenging at the rear end 50 of the cylinder and suction at the forward end, and correspondingly during alternate strokes of the piston unit, firing at the rear end of the cylinder and scavenging at the forward end and during the intervening strokes, suction at the rear end 55 and compression at the forward end, is repeated, as will be appreciated, a number of times per revolution of the engine equal to one half the total number of cylinders, that is to say 60 in the engine shown, six times.

As will be seen from the accompanying drawings, the cylinder unit is considerably more massive than the piston-unit. This is an important feature, for the excess of weight in the cylinder-unit over the piston-unit provides a flywheel effect in the rotation of the parts, with the result that if the said excess of weight is sufficient, the rotation of the cylinder-unit may be rendered substantially continuous, the piston-unit performing its reciprocation relatively to the cylinder-unit by moving alternately faster and slower than that unit.

Referring now to Figures 4 and 5, the modified construction of piston-unit illustrated in these figures is one in which the piston disc 8 is formed 75

- with radial projections 41 at each piston positioned around its periphery. These projections 41 are integral with the disc and in effect constitute in each case a central section of the piston, the two side sections 42 of which are of cylindrical contour and are bolted on to the opposed faces of the projection by means of bolts 42'. The composite piston thus produced may be fitted with piston rings 43.
10. The advantage of this modified construction shown in Figures 4 and 5 is that, as will be appreciated, the pistons are virtually integral with the piston disc which carries them, and, in consequence, the construction is admirably suited to 15 the thrust conditions prevailing in the engine as between the piston and the disc.

What I claim and desire to secure by Letters Patent is:—

1. A rotary internal combustion engine of the type referred to comprising in combination an annular rotary multi-cylinder unit, a co-operating rotary multi-piston unit co-axial with the cylinder unit, valve and ignition means operable to occasion explosions alternately on opposite sides 25 of the pistons, those on one side producing power strokes of the cylinder unit about the common axis of rotation of the units and those on the other side producing auxiliary strokes of the piston unit about said common axis and in the same 30 direction as the strokes of the cylinder unit, the auxiliary strokes of the piston unit serving to return the two units to their initial relative positions at the commencement of the power stroke of the cylinder unit and means comprising sta-

tionary reaction members cooperating with uni-directional clutch elements on the rotating units to prevent reverse rotation of each unit during the strokes of the other unit, the cylinder unit having a moment of inertia substantially exceeding that of the piston unit and constituting thereby a flywheel in the engine from which the power of the engine is arranged to be transmitted.

2. A rotary internal combustion engine of the type referred to comprising in combination an annular rotary multi-cylinder unit, a co-operating rotary multi-piston unit coaxial with the cylinder unit and valve and ignition means operable to occasion explosions alternately on opposite sides of the pistons, those on one side producing power strokes of the cylinder unit about the common axis of rotation of the units and those on the other side producing auxiliary strokes of the piston unit about said common axis and in the same direction as the strokes of the cylinder unit, the auxiliary strokes of the piston unit serving to return the two units to their initial relative positions at the commencement of the power stroke of the cylinder unit, detents on each unit co-operating with fixed circular reaction members concentric with the units, to prevent reverse rotation of each unit during the strokes of the other unit, the cylinder unit having a moment of inertia substantially exceeding that of the piston unit and constituting thereby a flywheel in the engine from which the power of the engine is arranged to be transmitted.

HENRY SCHULMAN.
